UNITED STATES PATENT OFFICE.

ANTOINE BARNAY, OF PARIS, FRANCE.

SYSTEM FOR TRANSMITTING ELECTRICAL IMPULSES.

Application filed June 4, 1925, Serial No. 34,982, and in France June 11, 1924.

The object of the present invention is a system for transmitting electrical impulses, which is suitable more particularly in automatic telephone systems, and generally in all 5 "step by step" switching systems.

The invention concerns automatic switching systems in which the connection is established by means of electrical impulses sent over the two wires of the calling line in 10 series.

In systems of this kind, the impulsive circuit, including the calling station, is established progressively until the last organ used for establishing the connection is operated. As a result of this, in order to maintain 15 all of the switches excepting the last in their operated positions, a second holding circuit is required.

Means have been provided for eliminating 20 this second circuit for inter-office trunks in automatic telephone systems, by the addition in these trunks of an impulse repeater which has the same function in respect to the second office, as the impulse sending device of 25 the calling station has to the originating office.

One of the objects of the present invention is the suppression of impulse repeaters.

With this end in view, the invention consists 30 of means employed for using one of the line wires for the impulsive circuit, and the other for maintaining and controlling the impulsive circuit.

These means are characterized in that the 35 circuit of the calling station is closed in series with a relay whose function is to produce:

1st. Impulses in a circuit comprising one 40 of the line conductors and in each of the serially related selector switches, a relay whose function is to control the operation of the associated selector.

2nd. The energization of a relay for establishing and maintaining the impulse circuit, 45 the circuit of the said relay comprising the other line conductor, and in each office by which the connection passes, a similar relay; this circuit remaining closed in each of the serially related selectors, until the final selector is directed to the called line, the deenergization 50 of these relays connecting up the talking circuit.

This invention permits the battery feed

and supervisory relays to be placed in the first selectors, and the incoming selectors 55 (which are least in number) instead of in the final selectors (which are greatest in number) as is actually the general practice, this effecting an economy desirable even in single office telephone system. 60

An application of the means of the present invention is particularly advantageous, and is characterized in that, between two stages of selection either one of the line conductors may be used for the impulsive circuit (the holding circuit being established over the line conductor not employed for 65 impulsing) and the choice of the conductor to be used for impulsing being determined by the digit received by the first stage of 70 the two selecting stages considered.

This disposition permits the realization, with a numbering scheme, for example decimal, the grouping of the trunks on a base of twenty. If the normal grouping of the 75 trunks is "X", the grouping of the trunks may be doubled and becomes "2X".

With this disposition, connections may be established through a tandem office, without the use, neither of additional digits in the 80 calling number, nor of register-sender equipment. A tandem office disposed according to this invention will have associated with each incoming selector, which establishes the connections local to the tandem office, a pre-selecting secondary switch which is always standing on an idle trunk leading to the following office, and a switching arrangement 85 whose operating position is determined by the line conductor chosen for the impulse circuit by the preceding selector, the switching arrangement connecting up either the selector local or the secondary switch to the incoming trunk.

The accompanying drawing represents, as 90 95 an example only, three of the preferred forms of realization of the invention.

In Fig. 1 is shown the circuit drawing of one form of realizing the invention. The selector circuits are not shown as they may 100 be any one of the well known "step by step" selectors.

In Fig. 2 is shown a second form of realization of the impulse circuit.

Fig. 3 is a diagram relative to the circuit 105 shown in Fig. 2.

In Fig. 4 is shown another form of realization of the invention, and Fig. 5 is a diagram showing the application of the circuit of Fig. 4.

On referring to Fig. 1, when the calling station is connected to a selector S_1 , impulses are sent by the impulse sender 1, of any of the well known types which produce interruptions in the line circuit. The line relay 2 has two windings, one 3 being connected between the battery and the line conductor 4, the other 5 between earth and the other line conductor 6. The impulses sent over the line cause relay 2 to alternately attract and release its armature 7. Relay 2 is shown as having two windings, but it might have only one winding and the impulses sent over one line conductor only.

When the calling station is connected to relay 2, this relay energizes in series with the station, and closes at 8 the following circuit: battery—9—7—8—10—earth. Relay 10, upon energizing, closes the circuit: battery—relay 12—11—13—and earth. Relay 12 energizes, prepares at 14 a holding circuit, and at 15 the impulsing circuit for relay 16.

When the impulse sender 1 is operated, at each interruption of the line circuit relay 2 falls back, and closes at 17 the following circuit: battery—resistance 9—contacts 7—17—15—18—relay 16—and earth. Relay 16 controls the operation of the selector, which is of the "step by step" type, and does not need to be described. The slow 35 to release relay 10 does not fall back during the series of impulses.

After the transmission of the first digit of the called number, when the wipers 19 and 20 are brought to rest on an idle line, relay 21 energizes, connects at 22 relay 12 to the line conductor 23, connects at 24 the impulse circuit to the other line conductor 25, and opens at 13 the original holding circuit of relay 12. As contact 22 is established before 13 is opened, relay 12 remains energized over the circuit: 22—wiper 19—line conductor 23—and earth, in the selector S_2 , which in the present example is represented as incoming selector in another office.

In the selector S_2 , relay 26 energizes in series with relay 12 of selector S_1 , over the circuit: line conductor 23—contact 55—winding of relay 26—contact 27—and earth. The impulse circuit is connected to relay 28 over the circuit: line conductor 25—contacts 30—29—winding of relay 28—and earth.

When the impulse sender is operated to send the second digit of the wanted number, at each interruption of the line circuit the circuit of relay 28 is closed by: battery—resistance 9—contacts 7—17—15—24—wiper 20—line conductor 25—contacts 30—29—winding of 28—and earth. Relay 28 controls the operation of the selector S_2 .

As explained for the selector S_1 , when the wipers of S_2 are brought to rest on an idle line, relay 31 energizes, connects at 32 the earthed line conductor 33 to relays 26 and 12 in series, and opens at 27 their local holding circuit. At 34 the impulse circuit is connected to line conductor 35.

The following selector S_3 is a hundreds selector in the same office as S_2 and S_4 is a line or final selector. S_3 and S_4 have each an impulsing relay indicated by 16—28, since these relays have the same functions as relays 16 of S_1 and 28 of S_2 , and have besides a switching relay indicated by 21—31, since the function of these relays is the same as relay 21 of S_1 and 31 of S_2 .

When the wipers of S_3 are brought to rest on the contacts of the wanted line, relay 21—31 energizes, opens the holding circuit of relay 26 in S_2 and relay 12 in S_1 , and in 37 and 38 connects up the wanted line, the impulse circuit being opened at 39.

In S_1 , relay 12 falls back and connects at 40 and 41 the battery feed relay 42 to the line. In S_2 relay 26 on falling back, opens at 44 the circuit of the slow to release relay 43, which was energized when relay 26 energized. Relay 43 does not fall back immediately when its circuit is opened and the circuit of relay 45 is closed at 46 and 47; relay 45 energizes, and connects relay 49 to the line at contact 48. Relay 49 energizes in series with relay 42, but on account of the high resistance of the two windings relay 49, relay 42 is not energized. At 50, relay 49 closes a new circuit for relay 43 before this relay has had time to fall back. Relay 45 on energizing connects at 51 and 52 the battery feed relay 56 to the called side of the line; closes at 53 and 54 the talking circuit and opens at 30 and 55 the shunts around the condensers in series with the lines conductors.

The talking circuit is now completely established.

When the called party takes down his receiver, relay 56 energizes and short-circuits at 59 the high resistance winding of relay 49. In selector S_1 , relay 42 energizes in series with the low resistance winding of relay 49, and in any well known manner operates a subscriber's meter and provides supervision on the calling line.

It is not necessary to describe the release of the connection, which is controlled by relay 10 of S_1 and 43 of S_2 , these relays falling back at the deenergization of 2 of S_1 and 42 of S_2 , when the calling party hangs up his receiver.

The arrangement shown in Fig. 2 is another application of the same principle, which presents the following important characteristics.

The impulses may be sent over either of the line conductors, the conductor not be-

ing used for the impulse circuit being employed for making a non-numerical selection, and for holding the selectors in operated position.

5. In the example represented, S_3' is a selector similar to S_3 , and S_4' a final selector.

The selector S_3' has two relays 16—28 and 21—31 the operation of which is the same as described above. It has besides a reversing relay 60 which is, or is not energized according to the digit received by the selector S_3' . Relay 60 on energizing reverses at contacts 61 and 62 the wipers 63 and 64.

The selector S_4' also has two relays 16—28 and 21—31; it has besides two wipers selecting relays 67 and 68.

Two cases are to be considered:

1st. The called digit is such that relay 69 is not energized. In the preceding selector, such as S_1 , relay 12 is connected in series with the lower winding of relay 67 in S_4' over the circuit: battery—relay 12—line conductor 65—wiper 64—conductor 74—contacts 69—70—lower winding of relay 67—and earth. Relay 67 energizes, closes at 71 a holding circuit by its upper winding, disconnects at 72 the lower winding of 68 from the line conductor, and connects at 73 the line conductor 75 to the impulse relay 16—28. Furthermore relay 67 prepares the connecting circuit for wipers 78 and 79, at contacts 76 and 77. From this point on relays 16—28 and 21—31 operate as described above.

2nd. The called digit is such as to cause the energization of relay 60. In this case, the relay 12 in the preceding selector such as S_1 is connected in series with the lower winding of relay 68 by the circuit: conductor 75—contact 61—wiper 63—conductor 75—and contacts 80—72.

Relay 68 energizes, closes a holding circuit by its upper winding at 81, disconnects at 70 the lower winding of relay 67 from conductor 74, connects at 82 the impulse relay 16—28 to conductor 74 and prepares at contacts 83 and 84 the connecting circuit for wipers 85 and 86.

Fig. 3 is the diagram of a practical application of the circuit shown in Fig. 2 to a telephone office having a capacity for 4,000 lines. This office has only two selecting stages. In the diagram, the first stage of selection is represented by the selector S_3' , and the second stage by the line selector S_4' , each of these selectors having twenty trunks per level, although the numbering system is decimal.

The line selector S_4' has access to 200 subscriber's lines, but it only receives two digits of the called number, the choice of the lines in one or the other hundred to which it has access being determined by the preceding selector and which causes the operation or the non-operation of relay 60 (Fig. 2, S_3).

The first selector S_3' has access to twenty groups of line selectors S_4' . It receives two digits of the called number, the first digit causing the wipers to be brought to rest on the group of lines corresponding to the called digit. This group of lines comprises five sub-groups. The second digit brings the wipers into contact with the first line in the determined sub-group, and causes the excitation if necessary of relay 60 in such a way as to release in this group ten different combinations.

The selection of an idle line in the chosen sub-group takes in the well known way.

The above described arrangement of selector S_3' can be applied to any type of selector.

Fig. 4 represents an arrangement in which an incoming selector and an organ which designed in the following by the name "tandem selector" are grouped together in the same office.

This arrangement consists of three parts of which two are entirely independent, one from the other, and a third which cooperates with one or the other of the first two, separately.

The two independent parts are the selector S , which for example may be similar to the selector S_3 , and the tandem switch CT. The third part consists of the group of relays GR. The tandem switch CT is arranged so that its wipers are always at rest on an idle line.

The group represented by Fig. 4 is chosen by a selector such as S_3' (and which may be situated in another office); this group can receive impulses either over the conductor 75, or over the conductor 74.

1st. The impulses come in over the conductor 74. In this case, relay 87 energizes in series with a relay, such as 12 (S, Fig. 1) by the circuit: earth—contacts 88—89—winding of 87—contacts 90—91—conductor 65—(relay 60 energized) and relay 72—to battery.

Relay 87 energizes, and remains energized over the circuit contacts 92—93—94—earth. Relay 87 disconnects at 95 relay 96 from the conductor 74; at 100, the circuit of relay 101 is closed, and this relay energizes.

Relay 101 connects at contacts 102 and 103, line conductors 74 and 75 through to the following selector (which may be in another office) via the wipers 104 and 105 which are always resting on the contacts of an idle line. Relay 87, the local circuit of which is opened at 93, is held in operated position by the wiper 105, which is earthed by the selector on the contacts of which the wiper is resting.

2nd. The impulses come in over the conductor 75. Relay 96 energizes over the circuit: earth—contacts 106—107—winding of 96—contacts 95—108—conductor 74—wiper

64—conductor 65 (relay 60 not being energized)—relay 12 (S_1 , Fig. 1)—and battery.

5 Relay 97 is held in operated position by contacts 109—93—94 and earth; at contact 90, relay 87 is disconnected from conductor 75, and at contact 110, the impulse relay 16—28 is connected to conductor by 91—110—98—and 99.

10 Impulse relay 16—28 of selector S_1 controls the operation of this switch as hereinbefore described. When the wipers come to rest on an idle line, relay 21—31 energizes and connects up the wipers 111 and 112 and the following selector, to the line conductor 15 74 and 75 by the contacts 113—114—, 93—98, and 91—108.

20 Relay 96, being in series with conductor 74, remains energized by earth from the following selector. Relay 45 has the same functions as relay 45 in selector S_2 , and is energized when the connection is established with the called line.

25 Fig. 5 is a diagram of the application of the arrangement shown in Fig. 4, in a telephone network having a tandem office B_t .

30 At B_d is represented an office having access to the office B_a , through the tandem office B_t . Each office is supposed to have a capacity for 10,000 lines, and that the subscribers' numbers consists of 5 digits. The digit indicating office B_t is the digit 5, that for office B_a is 6. When a subscriber in office B_d calls the digit 5, the selector S_e takes an idle line to office B_t , but in this 35 case relay 60 (S'_s , Fig. 2) is not energized and the incoming selector S_e at office B_t is used for establishing the connection with a subscriber in office B_t . The four following digits of the called number operate the local 40 selectors in office B_t .

45 If the first digit of the wanted number is 6, selector S_e takes an idle line to office B_t in the same group as when the first digit was 5, but in this case relay 60 (S'_s , Fig. 2) is energized, and the tandem switch is employed for routing the connection immediately to the selector S_s in office B_a , without the transmission of any supplementary digit.

50 It should be noted that the selector S_e can be replaced by another switch similar to CT, and which may have access either to selectors in office B_t , or to selectors in a second office such as B_a .

55 The selector S_s in office B_a could be replaced by an arrangement similar to the one composed of selector S_e and tandem switch CT in office B_t , and which would be operated by an appropriate combination of digits in the calling number. It is quite clear that 60 in this case the digit indicating one of the offices B_a would correspond to the indicating digit of office B_t , which in the case exposed above would be the digit 5.

65 One of the principal advantages of this arrangement is to have only one group of

outgoing trunks between office B_a and office B_t .

What I claim as my invention and desire to secure by Letters Patent is:

1. In an automatic telephone system, a 70 calling line, an impulse sending device in the circuit of the said line, a line relay, serially related selector switches connected by two conductor trunk lines, a magnet in each selector for controlling the setting of 75 the said selector the circuit of the magnet including a section of one of the conductors of the trunk line, an interrupter actuated by the line relay, and means, including the second conductor of the trunk line, for connecting the said section of the first conductor either to the said interrupter during the selection or to one of the conductors of the calling line at the end of the selection.

2. In an automatic telephone system as 85 claimed in claim 1, means for connecting the second conductor of the trunk line to the second conductor of the calling line.

3. In an automatic telephone system a 90 calling line, an impulse sending device in the circuit of the said line, a line relay, serially related selector switches connected by two conductor trunk lines, a magnet in each selector for controlling the setting of the 95 said selector, the circuit of the magnet including a section of one of the conductors of the trunk line, an interrupter actuated by the line relay, a switching device for connecting the said section of the first conductor either to the said interrupter during 100 the selection or to one of the conductors of the calling line at the end of the selection, and means including the second conductor of the trunk line for controlling the position of the said switching device.

4. In a multi-office automatic telephone system, a calling line, an impulse sending device in series with the said line, a line relay, serially related selector switches located in the several offices of the network 11 and connected by two conductor trunk lines, a magnet in each selector for controlling the setting of the said selector, the circuit of the magnet including a section of one of the trunk line conductors, an interrupter actuated by the line relay, a first switching device in the originating office for connecting the said section of the first conductor either to the said interrupter during the 12 selection or to one of the conductors of the calling line at the end of the selection, means in each of the other offices for holding the serially related selectors in operated position the said means being controlled by a switching device and means including the second conductor of the trunk line for controlling the position of the latter switching devices and that of the first switching device located in the originating office.

5. In an automatic telephone system, a 13

- calling line, an impulse sending device in series with the said line, a line relay, serially related selector switches connected by two conductor trunk lines, a magnet in each selector for controlling the setting of the said selector the circuit of the magnet including a section of one of the trunk line conductors, an interrupter actuated by the line relay, a switching device for connecting the 5 said section of the first conductor either to the said interrupter during the selection or to one of the conductors of the calling line at the end of the selection, a holding relay in the circuit of the second conductor of the 10 trunk line for operating the said switching device, means for energizing the said relay before the selection and means for opening the circuit of the said relay at the end of the selection.
10. In an automatic telephone system as claimed in claim 9 an interrupter in the second conductor of the trunk line and controlled by the holding relay for connecting this second trunk conductor to the corresponding conductor of the calling line on 15 the de-energization of the said relay.
11. In a multi-office automatic telephone system, a calling line, an impulse sending device in series with the said line, a line relay, serially related selector switches located in the several offices of the network and connected by two conductor trunk lines, a magnet in each selector for controlling the setting of the said selector the circuit of the magnet including a section of one of the 20 trunk line conductors, an interrupter actuated by the line relay, a first switching device in the originating office for connecting the said section of the first conductor either to the said interrupter during the selection 25 or to one of the conductors of the calling line at the end of the selection, means in each of the other offices for holding the serially related selectors in operated position the said means being controlled by a switching device, a first holding relay in the originating office for controlling the position of the first switching device, another holding relay in each other office for controlling the position of the switching device 30 in its respective office the circuit of the holding relays including the second trunk conductor, means for energizing the first holding relay before the selection, means for energizing each of the other holding relays before the operation of the selectors in the office to which the considered relay is located and means for opening the circuit of the said relays at the end of the selection.
35. In an automatic telephone system, a calling line, an impulse sending device in series with the said line, a line relay, serially related selector switches connected by two conductor trunk lines, a magnet in each selector for controlling the setting of the said selector, the circuit of the magnet including a section of one of the trunk line conductors, an interrupter actuated by the line relay, a switching device for connecting the 40 said section of the first conductor either to the said interrupter during the selection or to one of the conductors of the calling line at the end of the selection, a holding relay in the circuit of the second conductor of the trunk line for operating the said switching device, an energizing circuit for the holding relay including two interrupters, means for closing one of these interrupters at the first energization of the line relay and for maintaining it closed until the last de-energization of the said line relay, means for opening 45 the other interrupter after the energization of the holding relay, a locking circuit for the said holding relay including an interrupter closed on the energization of this relay, a switching device in each selector for prolonging the circuit of the holding relay to the following serially related selector and an interrupter disposed in the final selector for opening the circuit of the holding relay at the end of the selection.
50. In an automatic telephone system as claimed in claim 9 an interrupter in the second conductor of the trunk line and controlled by the holding relay for connecting this second trunk conductor to the corresponding conductor of the calling line on the de-energization of the said relay.
55. In a multi-office automatic telephone system, a calling line, an impulse sending device in series with the said line, a line relay, serially related selector switches located in the several offices of the network and connected by two conductor trunk lines, a magnet in each selector for controlling the setting of the said selector the circuit of the magnet including a section of one of the trunk line conductors, an interrupter actuated by the line relay, a first switching device in the originating office for connecting the said section of the first conductor either to the said interrupter during the selection or to one of the conductors of the calling line at the end of the selection, means in each of the other offices for holding the serially related selectors in operated position the said means being controlled by a switching device, a first holding relay in the originating office for controlling the position of the first switching device, another holding relay in each other office for controlling the position of the switching device in its respective office the circuit of the holding relays including the second trunk conductor, means for energizing the first holding relay before the selection, means for energizing each of the other holding relays before the operation of the selectors in the office to which the considered relay is located and means for opening the circuit of the said relays at the end of the selection.
60. In an automatic telephone system as claimed in claim 11 means for disconnecting the holding relays from the trunk line at the end of the selection.
65. In a multi-office automatic telephone system, a calling line, an impulse sending device in series with the said line, a line relay, serially related selector switches located in the several offices of the network and connected by two conductor trunk lines, a magnet in each selector for controlling the setting of the said selector the circuit of the magnet including a section of one of the trunk line conductors, an interrupter actuated by the line relay, a first switching device in the originating office for connecting the said section of the first conductor either to the said interrupter during the selection or to one of the conductors of the calling line at the end of the selection, means in each of the other offices for holding the serially related selectors in operated position the said means being controlled by a switching device, a first holding relay in the originating office for controlling the position of the first switching device, another holding relay in each other office for controlling the position of the switching device in its respective office the circuit of the holding relays including the second trunk conductor, means for energizing the first holding relay before the selection, means for energizing each of the other holding relays before the operation of the selectors in the office to which the considered relay is located and means for opening the circuit of the said relays at the end of the selection.

- vice in the originating office for connecting the said section of the first conductor either to the said interrupter during the selection or to one of the conductors of the calling line at the end of the selection, means in each of the other offices for holding the serially related selectors in operated position the said means being controlled by a switching device, a first holding relay in the originating office for controlling the position of the first switching device, another holding relay in each other office disposed in series with the preceding holding relay for controlling the position of the switching device in its respective office the circuit of the holding relays including the second trunk conductor, means for energizing the first holding relay before the selection, means for energizing each of the other holding relays before the operation of the selectors in the office to which the considered relay is located and means for opening the circuit of the said relays at the end of the selection.
14. In an automatic telephone system as claimed in claim 11 an interrupter in the circuit of each of the serially related holding relays excepting the first, an operating relay for each of the said interrupter, means for energizing this relay at the end of the selection and means for holding this relay energized until the end of the communication.
15. In an automatic telephone system as claimed in claim 11, an interrupter in the circuit of each of the serially related holding relays excepting the first, an operating relay for each of the said interrupters, the circuit of the said operating relay including two interrupters, one closed by the deenergization of the holding relay and the other closed by the energization of a slow to release relay, means for energizing the said slow to release relay on the energization of the holding relay, an auxiliary holding relay, means for energizing this relay on the energization of the interrupter operating relay and means for holding the said slow to release relay energized by the energization of the auxiliary holding relay.
16. In an automatic telephone system as claimed in claim 11, an interrupter in the circuit of each of the serially related holding relays excepting the first, an operating relay for each of the said interrupters, means for energizing this relay at the end of the selection, means for holding this relay energized until the end of the communication, an auxiliary holding relay the circuit of the said relay including the two conductors of the inter-office trunk line connecting the office in which is located the said relay considered and the preceding office and in which office the said circuit is closed, and an interrupter in the said circuit and closed by the energization of the operating relay.
17. In an automatic telephone system as claimed in claim 11 an interrupter in the circuit of each of the serially related holding relays excepting the first, an operating relay for each of the said interrupters, means for energizing this relay at the end of the selection, means for holding this relay energized until the end of the communication, a high resistance auxiliary holding relay, a preliminary energizing circuit for the said relay including one pole of the battery, an interrupter closed on the deenergization of the holding relay, a second interrupter closed on the energization of the slow to release relay, a third interrupter opened on the energization of the operating relay, the second conductor of the inter-office trunk line connecting the office in which is located the said relay considered and the preceding office, and a switching device in this last office arranged for connecting the said second trunk line conductor to the other pole of the battery either in series with the holding relay of the said office or in series with a battery feed relay, means for energizing the said slow to release relay in each office on the energization of its associated holding relay and a main energizing circuit for the auxiliary holding relay including the two conductors of the inter-office trunk line connecting the office considered and the preceding office in which the said circuit is closed by an interrupter closed on the energization of the operating relay.
18. In an automatic telephone system as claimed in claim 11, an interrupter in the circuit of each of the serially related holding relays excepting the first, an operating relay for each of the said interrupters, means for energizing this relay at the end of the selection, means for holding this relay energized until the end of the communication and a relay for feeding battery out on the trunk line connecting the office in which is located the relays considered either to a following office or to a called line, the circuit of the said battery feed relay including at least one interrupter closed on the energization of the operating relay.
19. In an automatic telephone system, a calling line, an impulse sending device in the circuit of the said line, a line relay, serially related selector switches connected by two conductor trunk lines, a magnet in each selector for controlling the setting of the said selectors the circuit of the magnet including a section of one of the conductors of the trunk line over which are sent impulses, an interrupter actuated by the line relay for producing the said impulses, means including the other trunk conductor, which serves as a holding conductor, for connecting the said section of the first conductor either to

the said interrupter during the selection or to one of the conductors of the calling line at the end of the selection and means for reversing between two serially related selectors the impulse conductor and the holding conductor in order to realize a supplementary selection.

20. In an automatic telephone system as claimed in claim 19, a selector having trunk reversing contacts, means for operating the said contacts and supplementary selecting relays in the following serially related selector each being connected to one of the trunk conductor and arranged to be energized when its associated conductor is employed for the holding conductor.

21. In an automatic telephone system as claimed in claim 19, a selector having trunk reversing contacts, means for operating the said contacts, two supplementary selecting relays in the following serially related selector each connected to one of the trunk conductors and arranged so as to be energized when inserted in the holding circuit, and

means for opening the circuit of one of these relays when the other is energized.

22. In an automatic telephone system as claimed in claim 19, a selector having trunk reversing contacts, means for operating the said contacts, two supplementary selecting relays in the following serially related selector each connected to one of the trunk conductors and arranged so as to be energized when inserted in the holding circuit, means for opening the circuit of one of these relays when the other is energized and means for connecting the selector controlling magnet to the trunk conductor chosen for the im- pulser.

23. In an automatic telephone system as claimed in claim 19, a selector, a non-numerical selecting switch, and means controlled by the inversion of the trunk conductors to connect the trunk line either to the selector or to the non-numerical selecting switch.

In testimony whereof I have signed my name to this specification.

ANTOINE BARNAY.
